GRINDING MACHINE

Raymond H. Cramer, Newark, N. J., assignor to
General Motors Corporation, Detroit, Mich., a
corporation of Delaware

Application September 24, 1937, Serial No. 165,565

5 Claims. (Cl. 51—103)

This invention relates to grinding machines and methods and comprises all of the features and aspects of novelty herein disclosed. In centerless grinding by the through feed method, roundness of the work is improved by passing the work several times through the grinding zone, the position of the work blade being different for successive passes. In other words, the work is initially ground above or below the line of centers of the grinding and the regulating wheels, the subsequent passes being successively nearer to the line of centers. This requires either several machines each with a different setting or a series of set-ups for one machine.

An object of the invention is to provide an improved grinding machine and method for completely finishing a surface of revolution in a single pass through the grinding zone and obtaining a progressive true roundness of the generated surface in any plane normal to the axis of the piece. Another object is to provide an improved grinding machine and method for accurately generating a contoured surface of revolution on a round work-piece. Another object is to provide a grinding machine in which the advantages of oscillating and centerless grinding by the infeed method are combined.

To these ends and also to improve generally upon machines and methods of this character, the invention consists in the various matters hereinafter described and claimed. In its broader aspects, the invention is not necessarily limited to the specific constructions and steps selected for illustrative purposes in the accompanying drawings in which—

Fig. 1 is a front elevation of the machine with some parts broken away and some in section.

Fig. 2 is an end elevation of Fig. 1 with the grinding wheel removed.

Fig. 3 is a plan view of a portion of the machine, the feeding wheel being in section.

Fig. 4 is a side view of a portion of the feeding wheel.

Fig. 5 is an end view of Fig. 4.

Fig. 6 is a side view of a portion of a thrust plate.

Fig. 7 is a plan view of a work supporting blade.

Fig. 8 is a front view of Fig. 7.

Fig. 9 is a right hand end view of Fig. 8.

Fig. 10 is a view similar to Fig. 8, the blade being tipped to expose the upper surface.

Fig. 11 is an enlarged perspective view of a portion of the machine.

The machines selected for illustration are especially adapted to grind the peripheries of

barrel-shaped rollers for bearings but it will be understood that the machines can readily be adapted to generate concave, convex, conical or other surfaces of revolution on a variety of objects. Such rollers produced by cold heading or by turning lathes, for instance, are preferably end ground to accurate length tolerances with the end faces flat and normal to the axis. These pieces are then ready to have the surface of revolution accurately generated by the machine.

The numeral 8 indicates a support or bed which is oscillated around a vertical axis 10 by any suitable mechanism. A base plate 12 having a standard 14 is secured by bolts 16 to the bed and has a bearing 18 for a rotating shaft 20. One end of the shaft is reduced in diameter and carries a worm wheel 22 driven by a worm 24 held between thrust bearings on a horizontal shaft 26 which is journaled in bearing lugs 28 on the standard. A pulley 30 drives the shaft 26 and, through the worm gearing, turns the shaft 20 clockwise at low speed, say two revolutions per minute. A flange 32 on the rear of the shaft is secured by bolts 34 to a rotary feeding wheel or carrier 36 which is dished to form a recess 38 receiving the end of a shaft 40 carrying a regulating wheel 42 whose peripheral surface is contoured to fit the work W which in this instance is a barrel shaped roller. The shaft 40 is journaled in a bearing 46 on a standard 48 whose base is slidably adjustable transversely of the shaft in a slideway 50 carried on the oscillating bed.

A narrow standard 52 is secured by bolts 54 to the bed 8 at a point near the axis 10 of oscillation. The upper portion of the standard is recessed opposite to the periphery of the carrier 36 to receive a removable guide or thrust plate 56 which is fastened by screws 58. Opposed to the regulating wheel to form a converging grinding throat is a grinding wheel 60 whose periphery is contoured like that of the regulating wheel and the work. The grinding wheel rotates downwardly at the work at high speed and the regulating wheel rotates upwardly at the work at much lower speed. Both wheels are adjustable towards the axis of oscillation to provide for wear, the grinding wheel having a suitable slide (not shown) for this purpose. Preferably, all of the parts described except the grinding wheel oscillate as a unit around the vertical axis 10 through a short arc, the broken line position of the grinding wheel in Fig. 3 indicating the relative oscillation which occurs between the grinding wheel on the one hand and the remaining parts on the other hand. The axis of oscillation is in the

plane of the grinding wheel and passes through the center of transverse curvature of the grinding wheel periphery.

The carrier 36 (see Figs. 4, 5 and 11) has its periphery provided with a series of equally spaced teeth 70 alternating with notches 72. The carrier preferably moves down at the grinding throat and the leading face 74 of each tooth is substantially radial or parallel to a closely adjacent radius. The face 74 lies at right angles to the bottom wall 76 of the notch while the rear face 78 of each tooth is perpendicular to the bottom wall 76 and parallel to the face 74. Extending perpendicularly into each bottom wall 76 is a tapped opening 80 for a blade fastening screw as will appear. That side of the carrier facing towards the thrust plate 56 has a flat annular face outside of a circular rib 82 to receive and support a toothed guide or thrust plate 86, see Fig. 6. The thrust plate 86 may be in the form of a single ring or may be in segments and it is removably attached to the side face of a carrier by screws 84. The thrust plate 86 has a series of teeth 88 alternating with tapered notches 90. The rear faces 92 of the teeth 88 substantially coincide crosswise with the rear faces 78 of the carrier teeth and each tooth 88 covers one side of a tooth 70 and a portion of an adjacent notch 72. The bottom wall 94 of each notch 90 is straight and substantially aligns with the bottom wall 76 of a carrier notch 72. The leading face 96 of each tooth 88 slants at, say 25°, to a radius.

A work supporting blade is removably carried in each notch and comprises an attaching or supporting portion 100 of rectangular section secured by a screw 102 entering the tapped opening 80. The portion 100 of each blade fits the tooth faces 74 and 78 and the bottom wall 76 of a notch 72. A narrow section 104 of each blade is of the same thickness as the toothed thrust plate 86 and fits a tapered notch 90 of the thrust plate 86, the narrow section of the blade having an upper wall 106 provided with the same inclination as the face 96 and engaging the latter. The blade has an extended portion 108 projecting laterally beyond the plate 86 over the regulating wheel periphery and into the space between the grinding wheel and the regulating wheel where it is provided with an upwardly and inwardly facing or bevelled surface 110 which is laterally contoured to conform to the work. The outer surface of the blade is curved as at 112, the center of curvature preferably being at the axis of oscillation and this places the work supporting portion of the blade close up to the contoured periphery of the grinding wheel 60 and just outside of the periphery of the regulating wheel 42. The work is conveniently supplied to the carrier from a magazine indicated at 114 and preferably arranged above the grinding throat and terminating near the top of the thrust plate 56.

As the feeding member or carrier 36 slowly turns clockwise, a work-piece W drops onto each contoured and inclined blade surface 110 between the fixed thrust plate 56 and one of the teeth 88 of the rotary thrust plate 86, the two thrust plates being parallel and spaced slightly farther apart than the length of the work and acting as guides for the end faces of the work. The next piece is held back by the curved surface 112 of the next blade until the carrier turns enough to let such next piece drop onto that next blade. The carrier moves each piece slowly

down sidewise while supported by the blade and the regulating wheel, the piece being rotated by contact with the regulating wheel which is moving in a direction opposite to that of the carrier. As the piece moves down to the grinding throat it is gradually ground to size, the carrier, thrust plates and the regulating wheel making several oscillations as a unit while grinding occurs. The carrier rotation may be intermittent if desired and the movement is desirably fast while the work is brought to grinding position and then slow so that sufficient oscillation strokes can occur at the grinding zone to generate an accurate contour. When the completed piece is carried below the grinding throat, it drops off the blade. The contour of the wheels is maintained by suitable dressing devices (not shown).

I claim:

1. In a machine for generating a curved surface on a round work-piece, a grinding wheel and a regulating wheel spaced apart to form a grinding throat, a thrust plate extending along one side of the grinding throat, a movable feeding member at the other side of the grinding throat and having a work supporting blade extending towards the thrust plate and adapted to travel through the throat peripherally of one of the wheels, and means providing for a relative movement of oscillation around an axis, between the grinding wheel on the one hand and the regulating wheel, feed member and thrust plate on the other hand; substantially as described.

2. In a machine for generating curved surfaces on round work, a grinding wheel and a regulating wheel spaced apart to form a grinding throat, the peripheries of the wheels being contoured to conform to opposite sides of the work, a feeding wheel alongside of the regulating wheel and having a plurality of work supporting blades projecting over the periphery of the regulating wheel, each blade having a contoured surface to conform to the work, a thrust plate extending along one side of the grinding throat to guide the ends of the work, means for slowly rotating the feeding wheel around an axis to traverse the work supporting blades through the grinding throat, and means operating during the travel of the blades to provide for oscillation around another axis of the regulating wheel, blades and thrust plate as a unit; substantially as described.

3. In a machine of the character described, a grinding wheel mounted to rotate on a fixed axis, a bed mounted to oscillate around an axis in the plane of the grinding wheel, a regulating wheel mounted on the oscillating bed and having its periphery opposed to that of the grinding wheel to form a grinding throat, a thrust plate mounted on the oscillating bed and closing one side of the grinding throat, a feeding member mounted on the oscillating bed and having a thrust plate closing the other side of the grinding throat, work supporting blades projecting into the throat from the feeding member, and means for rotating the feeding member around an axis to traverse the blades slowly through the throat while the bed and the parts supported thereby are oscillated around the bed axis; substantially as described.

4. In a machine of the character described, a grinding wheel and a regulating wheel spaced apart to form a grinding throat, a feeding wheel alongside of the regulating wheel and having its periphery notched, a thrust plate secured to the feeding wheel and having its periphery notched, and work supporting blades secured in the notches and projecting laterally over the pe-

periphery of the regulating wheel; substantially as described.

5. In a machine of the character described, a grinding wheel and a regulating wheel having their peripheries spaced apart to form a grinding throat, a feeding wheel alongside of the regulating wheel, a thrust plate secured to the feeding

wheel and having its periphery notched, work supporting blades secured to the feeding wheel and projecting through the notches of the thrust plate into the grinding throat; substantially as described.

5

RAYMOND H. CRAMER.
